VALVE ACTUATOR FOR A PRESSURIZED CONTAINER

Richard M. Monahan, Child's Road,
Basking Ridge, N.J. 07920

Filed Feb. 23, 1968, Ser. No. 10,699

Term of patent 14 years

Int. Cl. D9—02

U.S. Cl. D9—258

Fig. 1

Fig. 2

Fig. 3

Fig. 4

Fig. 5

Fig. 6

FIG. 1 is a perspective view of a valve actuator for a pressurized container embodying my new design;

FIG. 2 is a front elevational view on an enlarged scale;

FIG. 3 is a side elevational view thereof;

FIG. 4 is a rear elevational view;

FIG. 5 is a top plan view; and

FIG. 6 is a bottom plan view thereof.

I claim:

The ornamental design for a valve actuator for a pressurized container, as shown.
